UNITED STATES PATENT OFFICE.

CHARLES F. BOUCEK, OF CHICAGO, ILLINOIS, ASSIGNOR TO RUDA MANUFACTURING COMPANY, OF CHICAGO, ILLINOIS, A CORPORATION OF ILLINOIS.

WINDOW STRUCTURE.

Application filed March 4, 1926. Serial No. 92,113.

My invention relates to window structures particularly to that type which the window sash, in addition to being vertically slidable, is adapted to be swung on horizontal axes, and the important object of the invention is to provide improved and more efficient means for positively and securely locking the sash against accidental vertical movement when it has been swung to inclined position. The invention will be clearly understood by reference to the drawings, in which—

Fig. 1 is a front elevational view of a window frame with the sash therein;

Fig. 2 is an enlarged sectional view on the plane 2—2 of Fig. 1;

Fig. 3 is an enlarged inside view of a runner and locking mechanism;

Fig. 4 is a side view with the runner frame in section on line 4—4 of Fig. 3;

Fig. 5 is a sectional view on line 5—5 of Fig. 3;

Fig. 6 is a sectional view on line 6—6 of Fig. 3; and

Fig. 7 is a sectional view on line 7—7 of Fig. 3.

The window frame F, which receives the upper and lower sashes S and S', is constructed of sheet metal and comprises the sill section 10, the head section 11, and the side sections 12. The side sections have the inner and outer channels 13 and 14 for the lower and upper sashes respectively. These channels are lined by weather strip frames 15 and 16 of sheet metal and within these weather strip frames are the runner structures 17 and 18 to which the upper and lower sashes respectively are attached. These sash runners are each connected to a chain or cord 19 passing over a pulley 20 and connected at its other end with a sash weight (not shown) accommodated in the respective side frames 12.

The runner frames are of channel shape, as shown in Figs. 5 and 6, and each sash at each of its lower corners has a pivot pin 21 which is held and journaled in the lower end of the respective runner frames. Above each pivot connection a supporting bar 22 is pivoted at its outer end to the respective sides of the sash by means of a suitable pivot pin 23. At its inner end each bar is engaged by a pivot pin 24 which extends into the respective runner frames through a longitudinally extending slot 25 and is se-

cured to a cam or wedge structure 26. Such wedge structure is of a width to fit between the sides of the runner frame and as a sash is raised and lowered to closed and open position, respectively, this wedge will slide in the runner frame between the ends of the slot 25. Within the runner frame is the lever 27 which is pivoted a short distance above the slot 25 on the pin 28, a plate 29 extending transversely between the runner frame sides forming a bearing for the lever and forming also a strengthening support for the pivot pin. In the arrangement shown, the lever extends down along the front wall of the runner frame, and at its upper end it has pivoted thereto a brake plate 30 having at its outer end the brake flange or shoe 31 adapted to be extended through the opening 31' in the inner flange of the runner frame. At its lower end the lever has pivoted thereto a similar brake plate 32 whose flange or shoe 33 is adapted to be projected through the opening 34 in the front flange of the runner frame. Swing of the lever is controlled by the wedge structure 26. This structure may be an integral casting, its body part *a* being interposed between the lever and the inner side wall of the runner frame. Its base part *b* extends behind the lever to cooperate with the plate 29 to form bearing surface for the lever during swinging movement thereof. The wedge structure has also the end flange *c* through which the lever extends and which engages between the yoke part of the runner frame and the adjacent wall of the window frame channel to keep the lever in alignment with the runner frame. The pin 24 threads into or is riveted to the wedge structure and extends outwardly through the slot 25 to receive the respective bar 22 extending from the window sash.

Normally, when a window sash is closed, the respective wedge structures will be at the upper ends of the slots 25 so that the levers 27 will be free to swing to permit their brake shoe structures to be within the runner frames and with their friction or braking surfaces away from the side walls of the window frame channels. This arrangement is shown in connection with the upper sash S in Fig. 2. The sash is therefore free to be moved with its supporting runner frame up and down in the window frame channels.

In the normal position of the levers they

extend diagonally in the respective runner frames with the upper brake shoe structure just within the opening 31' and the lower brake shoe structure a distance inside of and away from the opening 34. The wedge bodies *a* of the wedge structures are at the upper or widest part of the spaces 35 between the levers and inner wall of the runner frames. Now, as soon as a sash is swung downward, the bars 22 connected therewith will cause the wedge structures to slide downwardly in the respective runner frames, and toward the narrow lower ends of the spaces behind the levers. The levers will therefore swing and during the first part of the swinging movement the upper brake shoe structures will be projected through the openings 31' into frictional engagement with the window frame channel side walls and the sash will immediately be primarily locked against vertical movement. When the sash reaches its lower or horizontal position as shown in Fig. 2 in connection with the lower sash, the wedge structures will have swung the levers to force the lower brake shoe structures out through the openings 34 and against the front side walls of the window frame channels and the sash will then be securely frictionally locked by the upper and lower brake shoes to the window frame and so long as the sash is swung in an open position, it will be impossible to shift its supporting runner frames vertically in the window frame channels. When a sash is swung toward closed position, the lower brake shoes will be released first, but the upper brake shoes will not be released until the sash has been returned practically to vertical position in the window frame. As the levers are comparatively long, the wedging action to force the brake shoes into braking position is gradually but forcibly applied and the levers are also sufficiently flexible and elastic so that their lower brake shoes can be swung into braking position after the upper brake shoes have been moved out.

My improved structure is simple and can be readily manufactured as all the parts are either in the form of simple castings or are formed by dies out of sheet metal. I do not desire to be limited to the exact construction and arrangement and operation shown and described as modifications can be made which will still come within the scope of the invention.

I claim:—

1. In a window structure, the combination of a window frame having upright side channels, runner frames slidable in said channels, a window sash pivoted to said runner frames to swing vertically into open or closed position, a lever in each runner frame, brake shoes on said levers, said runner frames having openings adjacent to said

brake shoes, wedge mechanism in said runner frames, and connections between said wedge mechanism and said sash adapted upon swinging of said sash to open position to actuate said levers to cause the brake shoes to be projected through said openings into friction engagement with the sides of said channels to thereby lock said sash against vertical movement in said channels.

2. In a window structure, the combination of a window frame having upright side channels, a runner frame slidable in one of said channels, a window sash pivoted to said runner frame for swinging movement, a lever pivoted in said runner frame, a brake shoe connected with said lever, said runner frame having an opening adjacent to said brake shoe, a wedge member slidable longitudinally in said runner frame alongside of said lever for wedging engagement therewith, and a connection between said sash and said wedge member adapted upon swinging movement of said sash to open position to cause said wedge member to actuate said lever to cause said brake shoe to be projected through said opening and into friction engagement with the side of said channel, whereby said sash will be locked with said runner frame against vertical movement.

3. In a window structure, the combination of a window frame having upright side channels, runner frames slidable in said channels, a window sash pivoted to said runner frames to swing relative thereto, a lever in each runner frame pivoted intermediate its ends and having brake shoes at its ends, said runner frames having openings adjacent to said brake shoes, a wedge member in each runner frame adapted for wedge cooperation with the respective lever and said wedge member being in position to permit swing of the lever to hold its brake shoes within said openings when said sash is parallel with said channels, and connections between said sash and said wedge members for causing wedge cooperation of said members with said levers when said sash is swung to open position, whereby said levers are swung to project their brake shoes through said openings and into friction engagement with the side walls of said channels to thereby lock said runner frames against movement in said channels, when said sash is swung away from parallel position in said channels.

4. In a window structure, the combination of a window frame having side channels, runners slidable in said channels, a window sash pivoted at its lower corners to said runners, said sash being adapted to swing upwardly into closed position or downwardly into open position, each runner having a longitudinal slot, bars secured to said sash, a wedge member in each runner connected through said slot with the respective bar

- whereby vertical swing of said sash will cause longitudinal movement of said wedge members in said runners, brake shoe structures in each runner, said brake shoe structures being normally disengaged from the sides of said channels to permit vertical movement of said runners in said channels, and means whereby downward swing of said sash will cause wedge co-operation of said wedge members and brake mechanisms to force said brake shoes into engagement with the channel sides to thereby lock said runners against vertical movement in said channels.
5. In a window structure, the combination of a window frame having side channels, runners slideable in said channels, a window sash pivoted at its lower corners to said runners to swing vertically relative thereto, a brake lever in each runner having a brake shoe, each runner adjacent said shoe having an opening, a cam member slideable in each runner to cooperate with the respective brake lever to cause actuation thereof to force its brake shoe through said opening and into engagement with the channel side to lock the runner against vertical movement when the sash is opened, and a connection between the sash and said cam members for controlling the operation thereof.
10. wedge members and brake mechanisms to force said brake shoes into engagement with the channel sides to thereby lock said runners against vertical movement in said channels.
15. 5. In a window structure, the combination of a window frame having side channels, runners slideable in said channels, a window

sash pivoted at its lower corners to said runners to swing vertically relative thereto, a brake lever in each runner having a brake shoe, each runner adjacent said shoe having an opening, a cam member slideable in each runner to cooperate with the respective brake lever to cause actuation thereof to force its brake shoe through said opening and into engagement with the channel side to lock the runner against vertical movement when the sash is opened, and a connection between the sash and said cam members for controlling the operation thereof.

In witness whereof, I hereunto subscribe my name this 1st day of March, 1926.

CHARLES F. BOUCEK.
